DESCRIPTION

FIG. 1 is a perspective view of a laryngoscope blade.

FIG. 2 is a top plan view of the laryngoscope blade.

FIG. 3 is a rear elevational view of the laryngoscope blade.

FIG. 4 is a right side elevational view of the laryngoscope blade.

FIG. 5 is a left side elevational view of the laryngoscope blade.

FIG. 6 is a bottom plan view of the laryngoscope blade.

FIG. 7 is a front elevational view of the laryngoscope blade.

The broken lines shown in FIGS. 1-7 are included for the
purpose of illustrating environmental elements only and form
no part of the claimed design.
